RESISTOR ASSEMBLY

George J. Mucher, Rochester, N. H., assignor to Clarostat
Mfg. Co., Inc., Dover, N. H., a corporation of New
York

Application November 24, 1954, Serial No. 33,225

Term of patent 14 years

(Cl. D26—1)

Fig. 1

Fig. 2

Fig. 3

Fig. 4

Figure 1 is a top plan view of a resistor assembly showing my new design;

Figure 2 is a side elevation;

Figure 3 is an end view; and

Figure 4 is a bottom plan view.

The broken line showing of a representative plug-in strip is for illustrative purposes only.

I claim:

The ornamental design for a resistor assembly, as shown and described.
